UNITED STATES PATENT OFFICE.

HERMAN BOCK, OF MERIDEN, CONNECTICUT.

MACHINE FOR HARDENING KNIFE-BLADES.

1,350,697.

Specification of Letters Patent. Patented Aug. 24, 1920

Application filed December 5, 1919. Serial No. 342,637.

To all whom it may concern:

Be it known that I, HERMAN BOCK, a citizen of the United States, residing at Meriden, in the county of New Haven and State 5 of Connecticut, have invented a new and useful Improvement in Machines for Hardening Knife-Blades; and I do hereby declare the following, when taken in connection with the accompanying drawings and 10 the characters of reference marked thereon, to be a full, clear, and exact description of the same, and which said drawings constitute part of this application, and represent, in—

15 Figure 1, a plan view of a knife-blade hardening machine constructed in accordance with my invention.

Fig. 2, a view thereof in side elevation with its semi-circular flame-reflector in vertical central section.

20 Fig. 3, an enlarged detached broken plan view of the blade-carrying wheel.

Fig. 4, a corresponding edge view thereof, showing three knife-blades suspended 25 therein.

Fig. 5, a sectional view thereof on the line 5—5 of Fig. 3 with the pivotal blade-clamp removed but with a knife-blade engaged with an abutment-finger of the gage-ring.

30 Fig. 6, a detached plan view of one of the blade-clamps.

Fig. 7, a view thereof in side elevation.

Fig. 8, a view thereof in front elevation.

Fig. 9, a detached plan view of the gage- 35 ring.

Fig. 10, a detached broken plan view of one of the blade-clamp rods.

Fig. 11, a detached plan view of the semi-circular burner.

40 Fig. 12, a view thereof partly in elevation and partly in section.

Fig. 13, a view thereof in transverse section on the line 13—13 of Fig. 12.

My invention relates to an improved ma- 45 chine for hardening knife-blades and the like, the object being to provide for the purpose indicated a simple, compact and convenient machine having a large capacity for work and constructed with particular refer-

50 ence to avoiding the hardening of the blade-heels, whereby it becomes unnecessary to draw their temper prior to drilling and fitting them.

With these ends in view my invention 55 consists in a knife-blade hardening machine having certain details of construction as

will be hereinafter described and pointed out in the claims.

In carrying out my invention as herein shown, I employ a work or blade-carrying 60 wheel 14 arranged to revolve in a horizontal plane and thereto mounted upon a vertical shaft 15, the lower end of which turns in a bearing 16 fastened to the machine-frame 17 and the upper end of which turns 65 in a bearing 18 in the end of the overhanging arm of a bracket 19 also secured to the machine-frame. The said shaft mounts a bevel gear 20 meshed into by a bevel pinion 21 at the inner end of a shaft 22 the outer 70 end of which mounts a gear wheel 23 driven by a pinion 24 on a shaft 25, the outer end of which carries an idle pulley 26 and a driven pulley 27, whereby the wheel 14 is continuously rotated rather than having 75 step-by-step rotation imparted to it.

The work or blade-carrying wheel 14 is formed at regular intervals in its periphery with rectangular radial work-receiving slots 28, all of which are intersected near their 80 lower ends by a circumferential deep horizontal slot 29 extending inward to their inner walls as shown in Fig. 5. Each of the slots 28 receives a pivotal blade-clamp having a body 30, an upstanding operating-arm 85 31 at the outer end thereof, and a depending clamping-face 32, the said body being perforated as at 33 for the reception of a pivot 34 and perforated as at 35 to receive the outer end of a rod 36, the inner end of which 90 is attached to the outer end of a spring 37 the inner end of which is attached to the hub 38 of the wheel as shown in Fig. 1. As will be seen by reference to Fig. 3, the blade-clamps are pivoted to one side of the respective slots 28 in which they operate, the horizontal body-portions 30 of the clamps swinging in the horizontal slots 29 in the wheel 14. The slots in the wheel, the blade-clamps in the slots, the rods and the springs, as thus 100 described, are all radially arranged with respect to the axis of the wheel as shown in Fig. 1. Normally, the springs 37 hold the blade-clamps in their blade-gripping positions, as shown in Fig. 3 in which their 105 clamping-faces 32 impinge upon the opposite or forward side walls of the radial slots 29. For automatically opening the clamps in succession preparatory to feeding the knife-blades 39, I employ an initial clamp-opener 40 secured to the bracket-arm 19, as shown in Fig. 1, in such inclined position

that as the wheel 14 revolves the upstanding operating-arms 31 of the clamps will be successively engaged with it, whereby the clamps will be turned on their pivots against 5 the tension of their springs 37 and thrown back into their open positions in which the slots 28 will be virtually cleared for the reception of the heels 41 of the knife-blades. As the wheel revolves, the arms of the 10 clamps will be carried past the clamp-opener and abruptly snapped by their springs 37 into their closed or blade-gripping positions. During the brief interval of the passage of the clamps past the clamp-openers, the 15 knife-blades 39 will be fed by hand into the machine and so momentarily held until the clamps are released for gripping them.

In the same manner the clamps are momentarily swung into their open positions 20 for dropping the blades through an opening 42 in the machine-frame into a tank 43 of tempering oil, by means of a secondary inclined clamp-opener 44 secured by screws 45 to the machine-frame as shown in Fig. 3. 25 The knife-blades 39 are manually inserted by an upward movement of the hand of the operator into the slots 28 in the wheel 14, whereby the heels 41 of the blades are located within the slots 28 and so prevented 30 from being sufficiently heated to be hardened when immersed in the oil in the tank. To gage the positioning of the knife-blades in the wheel, I employ a gage-ring 46 fitting over the upper portion of the periphery of 35 the wheel and secured in place by screws 47. This ring is provided with as many inwardly-extending stop-fingers 48 as there are slots 28 in the wheel, these fingers extending into the said slots as shown in Fig. 40 5 and acting as abutments for the blade-heels 41 so that the blades being inserted from beneath and lifted against the stop-fingers 48 will all be heated uniformly. By providing each machine with an inter- 45 changeable set of gage-rings, varying in width, it is apparent that the extent to which the blade-heels 41 are inserted into the ring 14 may be regulated as desired.

As the wheel revolves, the knife-blades 50 depending from it, travel in a circular path through a segmental heating-passage 49 formed between the convex rear face of a semi-circular gas-burner and the concave forward face of a flame-reflector. The said burner consists, as shown, of a series of burner tubes 50 embedded in insulating material 51 and having their exposed rear faces perforated, the lower ends of the said tubes being connected with a feed-tube 52 to which 55 air and gas is supplied. The said flame-reflector consists of a mass of refractory material such as asbestos confined within a shell 53. Through the passage 49 aforesaid, the suspended knife-blades travel as the 60 wheel revolves, being exposed in their transit 65

through this passage to the action of jets of gas flames issuing from the burner tubes, but the wheel and the burner tubes are so positioned respectively that the flames are practically confined to impingement upon the 70 knife-blades proper and do not reach upward to the blade-heels which are partly confined at least within the slots of and protected by the blade-carrying wheel 14.

In the operation of my improved machine, 75 the operator feeds the knife-blades into the constantly revolving wheel as the open slots therein are successively presented to him by its rotation and the successive opening of the blade-clamps. He momentarily holds 80 the blades in the respective slots until the clamps are snapped into their gripping positions by passing by and so clearing the initial clamp-opener 39. The knife-blades thus suspended from the wheel, travel 85 through the heating-passage 49 after which they are automatically released by the action of the secondary clamp-opener 44 when they are dropped by gravity into the oil tank 43. The action of the wheel being continuous and the operator being able to feed the knife-blades with great rapidity, the machine is given a large capacity for work. Moreover, the blade-heels are not so heated 90 that it is necessary to draw their temper for subsequently mounting and adjusting the blades. Furthermore, the machine is so open in character that it becomes unnecessary to resort to artificial means for cooling the carrying-wheel or any other part. It is 95 a great advantage to fractionally harden the blades in the sense that the blade-heels are not hardened as well as the blades proper, whereas generally in such machines the blades have to be uniformly hardened, necessitating drawing the temper of their heels for drilling them and adjusting the blades when they are mounted in knife-handles. It will be understood that my machine though 100 primarily designed for hardening knife-blades is not so limited but may be used 105 equally well for other like hardening operations.

I claim:

1. A hardening machine having a horizontally arranged work-carrying wheel, pivotal, spring-actuated, work-holding clamps carried thereby and constructed and arranged for exposing the part of the work to be hardened below the lower face thereof; 115 means for automatically opening the said clamps for inserting the work prior to heating, and releasing it after heating; and a semi-circular heating passage located below the plane of the lower face of the wheel in 120 position to have the exposed lower portions of the work carried through it.

2. A hardening machine having a horizontally arranged work-carrying wheel the periphery of which is formed with radial 130

- work-receiving slots; spring-actuated, pivotal, work-holding clamps operating in the said slots for holding the work with the portions thereof to be hardened exposed below the plane of the lower face of the wheel; means for opening the said clamps for feeding and for releasing the work; and a semi-circular heating passage located below the plane of the lower face of the wheel in position to have the depending portions of the work passed through it in the turning of the wheel.
3. A hardening machine having a horizontal work-carrying wheel formed in its periphery with a series of radial work-receiving slots, spring-actuated pivotal clamps operating in the respective slots, a ring-gage applied to the wheel for gaging the insertion of the knife-blades into the slots in which they are gripped by the said clamps, and a heating-passage through which the work is carried by the wheel.
4. A hardening machine having a horizontally arranged work-carrying wheel having a series of radial work-receiving slots and with a horizontal circumferential groove intersecting all of the said slots, a series of clamps pivoted in the said horizontal groove and swinging into said radial slots, means for operating the clamps to grip and to release the work and a heating-passage through which the blades are carried by the rotation of the wheel.
5. A hardening machine, having a horizontally arranged work-carrying wheel provided with peripheral work-receiving slots; pivotal, spring-actuated, work-holding clamps mounted in the wheel and operating in the said slots to hold the work with the portion thereof to be hardened depending below the plane of the lower face of the wheel; means for predetermining the extent to which the work may be entered into the said slots and, therefore, its dependence below the wheel; means for operating the clamps for feeding the work into the wheel; a semi-circular heating passage located below the plane of the lower face of the wheel

by which the depending lower portions of the work are carried through the said passage; and means for operating the clamps for the discharge of the work from the wheel after being heated in the said passage.

6. A hardening machine having a horizontally arranged work-carrying wheel formed with peripheral, radial work-receiving slots, a series of work-clamps mounted in the wheel and corresponding in number to the said slots, means for initially opening the said clamps to permit the insertion of the work into the said slots, means for heating the work during the travel of the wheel, means for releasing the work from the said clamps after it has been heated, and means applied to the upper portion of the wheel for predetermining the extent to which the work may be inserted into the wheel and thus gaging those portions of the work which are not to be tempered.

7. A hardening machine having a work-carrying wheel turning in a horizontal plane and formed in its periphery with radial work-receiving slots, work-clamps for the said slots, means for operating the said clamps in gripping and releasing the work, and a gage-ring applied to the upper portion of the wheel and provided with a series of inwardly extending stop-fingers entering the said slots and gaging the introduction of the work thereinto through the lower portions of the slots.

8. A hardening machine having a work-carrying wheel, means for mounting work therein, and a heating-passage through which the work is carried by the wheel, the said passage being formed between the convex face of a semi-circular burner and the concaved face of a corresponding flame-reflector.

In testimony whereof I have signed this specification in the presence of two subscribing witnesses.

HERMAN BOCK.
